(57) **CLAIM**

The ornamental designs for the ice melting tablet for melting ice and snow, as shown and described.

DESCRIPTION

FIG. 1 is a perspective view of an ice melting tablet in accordance with the present invention;

FIG. 2 is another perspective view of the ice melting tablet of FIG. 1;

FIG. 3 is a top plan view of the ice melting tablet of FIG. 1; FIG. 4 is a bottom plan view of the ice melting tablet of FIG. 1; and,

FIG. 5 is a side view of the ice melting tablet of FIG. 1, with the other side views being identical.
